FENCE OR SPLASH BACK STRUCTURE FOR
COOKING STOVES AND RANGES

Alfred J. Reedy, Battle Creek, Mich., assignor to
Detroit Michigan Stove Company, Detroit,
Mich., a corporation of Michigan

Application November 5, 1947, Serial No. 784,105

11 Claims. (Cl. 126—214)

1

This invention relates to improvements in fence or splash back structure for cooking stoves and ranges.

The main objects of this invention are:

First, to provide a cooking stove or range having a fence or splash back wall of substantial height which may be disassembled for minimizing the size of crating or packing containers.

Second, to provide a structure having these advantages in which the splash back wall comprises a relatively low base fence portion formed integrally with the top and a relatively high top fence portion or member which may be removed as a unit from the base fence portion but which when erected is very secure and rigid, and one in which the top portion may be quickly erected or disengaged without the aid of tools.

Third, to provide a structure having these advantages in which the top fence portion constitutes a housing for control fixtures of the stove or lamps and the like.

Fourth, to provide a structure having these advantages which may be very economically produced.

Further objects pertaining to details and economies of the invention will appear from the description to follow. The invention is defined in the claims.

A structure which embodies the features of the invention is clearly illustrated in the accompanying drawing, in which:

Fig. 1 is a fragmentary front elevation of a gas stove or range embodying my invention.

Fig. 2 is an enlarged fragmentary view in vertical section on line 2—2 of Fig. 1, the top fence member being shown as disengaged from the base fence member and arranged on the stove top.

Fig. 3 is an enlarged fragmentary view in vertical section on line 3—3 of Fig. 2 showing details of the detachable coupling members for the top and base fence members.

Fig. 4 is a fragmentary perspective exploded view showing structural details and relative proportions of the base and top fence members and of the tongue and socket coupling members therefor.

Fig. 5 is a conventionalized end elevation of the stove with a crate indicated by dotted lines, the removable top fence member being shown as detached from the base member and arranged within a carton and the carton taped to the top of the stove.

The embodiment of the invention illustrated comprises a stove top 1 formed as a stamping and having downturned end flanges 2. The stove

2

body 3 is provided with inturned top flanges 4 at its ends, the end flanges of the top having inturned portions 5 resting on the flange 4.

The top has a base fence or splash back member 6 formed integrally therewith comprising a front wall 7 and end wall 8 continuous with the top and the end flanges thereof as shown in the drawing. The front and end walls of the base fence member are provided with inturned flanges 9 and 10 respectively. Corner plates 11 are arranged within the corners of the base fence member on the under side of the flanges 9 and 10 and welded thereto as indicated at 12.

The top fence member comprises a front wall 13 and end walls 14 formed integrally and complementary to the front end walls of the base fence member, that is, they are of such dimensions at the bottom as to correspond to the top dimensions of the base fence member. These walls have inturned flanges 131 and 141 at the bottom edges thereof. This top fence member is provided with a top 15 extended forwardly into a nose portion 16 which constitutes a housing for lamps as 17, the projecting portion 16 being provided with windows 18 in proper relation to the lamp. A thermostat control member 19 is mounted in the front wall, the operating connections for which are not illustrated. These parts are illustrated to bring out the fact that the top fence member is adapted as a housing for fixtures.

The top and end walls of the top fence member have inturned flanges 20 and 20', the back wall 21 being detachably secured to the top fence member by means of screws as 22. The corner plates 23 are secured on the under sides of the front and end flanges of the top fence member at the corners thereof.

The stove is provided with a back wall 24 which is outwardly offset at its upper edge as at 25 providing a recess 26 for the lower end of the back wall 21 which projects below the side walls of the top fence member. A beading or joint strip 27 desirably formed of plastic material is provided to close the joint between the base and top fence or splash back members, this strip being preferably of T section with the central arm disposed on the under side of the inturned flanges 131 and 141 and secured thereto by screws 28. This strip not only covers the joint but is desirably contrastingly colored and serves as an ornamental beading.

The forming of the splash back or rear fence of the stove of sections is of great advantage in that it permits a relatively high fence or splash

back in which the parts may be readily formed as stampings without excessive draw, and the parts may be enameled with a minimum of defective parts. The top splash back member is detachably mounted by means of the coacting socket and tongue members 29 and 30. The socket member 29 is formed of a plate-like body portion having inturned edge flanges 31 adapted to receive the plate-like tongue or dowel member 30. The socket member has an attaching flange 32 at its upper end which is secured on the under side of the corner plates 11. The tongue or dowel member 30 has an attaching flange 33 at its upper end which is secured to the under side of the corner plates 23 of the top member. The socket members depend within the base fence member while the dowel or tongue members project from the bottom of the top fence member. The dowel member 30 is beveled at 34 to facilitate engagement with the socket.

With the parts thus arranged the top member can be mounted upon the bottom member of the fence without the aid of tools. It can be readily removed should occasion require to afford access to the fixtures housed within the top member, or in the event the finish of the top member shall be injured or chipped. Another main advantage is that the stove may be packed in a crate designated by the numeral 35 of substantially less height than would be required if the splash back were of one piece of the top splash back member fixedly mounted on the bottom member.

For shipment I provide a carton 36 of suitable dimensions to receive the top fence member as shown in Fig. 5 with the exception of the dowel members 30 which project from the carton. The top of the carton 37 is arranged under the members 30 as is shown in Fig. 5 and desirably overlie the base fence member. Adhesive tapes 38 and 40 are employed to secure the carton in position, these being lapped upon the ends of the stove as indicated in Fig. 5.

With this arrangement the parts are effectively protected and the crate may be of substantially less vertical dimensions than would be otherwise required, this resulting in a saving of material and shipping space. Since the top fence member can be easily erected without the aid of tools the stove may be shipped or delivered direct to the customer and easily erected. In the event the top fence member is injured it can be readily returned to the dealer or manufacturer in the carton 36. In that case the dowels would preferably be removed; they are desirably secured by bolts indicated at 39.

I have illustrated and described my invention in a highly practical commercial embodiment. I have not attempted to illustrate or describe other embodiments or adaptations which I contemplate as it is believed this disclosure will enable those skilled in the art to embody or adapt my invention as may be desired.

Having thus described my invention what I claim as new and desire to secure by Letters Patent is:

1. A stove or range including a top having downwardly projecting end flanges and an upwardly projecting fence base member formed integrally therewith, said base member comprising front and end walls continuous with the top and the end flanges thereof, the front and end walls of the base member having inturned top flanges, corner plates disposed within the fence base member below said flanges thereof and fixedly

secured thereto, sockets comprising plates having inturned edges adapted to receive a plate-like dowel member, said sockets having supporting flanges at their upper ends mounted on said corner plates with the sockets depending within the fence base member, a top fence member comprising front and end walls complementary to the front and end walls of said base member and having inturned flanges at their bottom edges, corner plates disposed below said flanges of said top fence member at the corners thereof and secured thereto, plate-like socket engaging dowels secured to said corner plates of said top fence member and removably engageable with the sockets of said fence base member and acting to support the fence top member in erected position when engaged with said sockets, said fence top member being provided with a detachable back wall projecting below the front and end walls thereof, a stove back wall extending across the rear of the fence base member and rearwardly offset at its upper edge to receive the downwardly projecting end of said top fence member back wall, and a joint strip of T section mounted on said fence top member and extending across the front and ends thereof to cover the joint between the fence base and top members when the fence top member is in erected position.

2. A stove or range including a top having downwardly projecting end flanges and an upwardly projecting fence base member formed integrally therewith, said base member comprising front and end walls continuous with the top and the end flanges thereof, the front and end walls of the base member having inturned top flanges, corner plates disposed within the fence base member below said flanges thereof and fixedly secured thereto, sockets comprising plates having inturned edges adapted to receive a plate-like dowel member, said sockets having supporting flanges at their upper ends mounted on said corner plates with the sockets depending within the fence base member, a top fence member comprising front and end walls complementary to the front and end walls of said base member and having inturned flanges at their bottom edges, corner plates disposed below said flanges of said top fence member at the corners thereof and secured thereto, plate-like socket engaging dowels secured to said corner plates of said top fence member and removably engageable with the sockets of said base fence member and acting to support the fence top member in erected position when engaged with said sockets, and a joint strip of T section mounted on said fence top member and extending across the front and ends thereof to cover the joint between the fence base and top members when the fence top member is in erected position.

3. A stove or range including a top having downwardly projecting end flanges and an upwardly projecting fence base member formed integrally therewith, said base member comprising front and end walls continuous with the top and the end flanges thereof, the front and end walls of the base member having inturned top flanges, corner plates disposed within the fence base member below said flanges thereof and fixedly secured thereto, sockets comprising plates having inturned edges adapted to receive a plate-like dowel member, said sockets having supporting flanges at their upper ends mounted on said corner plates with the sockets depending within the fence base member, a top fence member comprising front and end walls complementary to the front and

end walls of said base member and having in-turned flanges at their bottom edges, corner plates disposed below said flanges of said top fence member at the corners thereof and secured thereto, plate-like socket engaging dowels secured to said corner plates of said top fence member and removably engageable with the sockets of said base fence member and acting to support the fence top member in erected position when engaged with said sockets, said top fence member being provided with a detachable back wall projecting below the front and end walls thereof, and a stove back wall extending across the rear of the fence base member and rearwardly offset at its upper edge to receive the downwardly projecting end of said top fence member back wall.

4. A stove or range including a top having downwardly projecting end flanges and an upwardly projecting fence base member formed integrally therewith, said base member comprising front and end walls continuous with the top and the end flanges thereof, the front and end walls of the base member having in-turned top flanges, corner plates disposed within the fence base member below said flanges thereof and fixedly secured thereto, sockets comprising plates having in-turned edges adapted to receive a plate-like dowel member, said sockets having supporting flanges at their upper ends mounted on said corner plates with the sockets depending within the fence base member, a top fence member comprising front and end walls complementary to the front and end walls of said base member and having in-turned flanges at their bottom edges, corner plates disposed below said flanges of said top fence member at the corners thereof and secured thereto, and plate-like socket engaging dowels secured to said corner plates of said top fence member and removably engageable with the sockets of said base fence member and acting to support the fence top member in erected position when engaged with said sockets.

5. A stove or range including a top having a relatively low upwardly projecting chambered fence base member formed integrally therewith and comprising enclosing walls including front and end walls having in-turned top flanges, sockets vertically elongated and disposed within the chamber of said fence base member adjacent the ends thereof in supported depending relation to said top flanges, a relatively high top chambered fence member comprising enclosing walls including front and end walls of said base member and having in-turned flanges at their bottom edges, socket engaging tongues vertically elongated and mounted on said top fence member flanges adjacent the ends thereof and projecting downwardly therefrom for vertically sliding engagement within said elongated sockets in the chamber of said fence base member and acting to support the top fence member in erected supported position on the base fence member and permitting removal of the top fence member as a unit and preventing forward tilting of the top fence member relative to the base fence member when the tongues are engaged in the slots, said top fence member being provided with a detachable back wall, the top fence member constituting a housing for stove fixture elements, a joint strip mounted on said top fence to telescopically overlap the upper end of the fence base member thereby concealing the joint between the members when the top fence member is in erected position, and a stove back wall at the rear of the fence base mem-

ber, adjacent edges of said back walls being in overlapping relation when the top fence member is in erected position.

6. A stove or range including a top having a relatively low upwardly projecting chambered fence base member formed integrally therewith and comprising enclosing walls including front and end walls having in-turned top flanges, sockets vertically elongated and disposed within the chamber of said fence base member adjacent the ends thereof in supported depending relation to said top flanges, a relatively high top chambered fence member comprising enclosing walls including front and end walls complementary to the front and end walls of said base member and having in-turned flanges at their bottom edges, socket engaging tongues vertically elongated and mounted on said top fence member flanges adjacent the ends thereof and projecting downwardly therefrom for vertically sliding engagement within said elongated sockets in the chamber of said fence base member and acting to support the top fence member in erected supported position on the base fence member and permitting removal of the top fence member as a unit and preventing forward tilting of the top fence member relative to the base fence member when the tongues are engaged in the slots, and a joint strip mounted on said top fence to telescopically overlap the upper end of the fence base member thereby concealing the joint between the members when the top fence member is in erected position.

7. A stove or range including a top having a relatively low upwardly projecting chambered fence base member formed integrally therewith and comprising enclosing walls including front and end walls, sockets mounted upon and housed within said frame base member adjacent the ends thereof, a relatively high top chambered fence member comprising front and end walls complementary to the front and end walls of said base member, socket engaging vertically elongated tongues on said top fence member disposed adjacent the ends thereof and projecting downwardly therefrom for vertically sliding engagement within said elongated sockets in the chamber of said fence base member and acting to support the top fence member in erected supported position on the base fence member and permitting removal of the top fence member as a unit, said top fence member being provided with a detachable back wall, the top fence member constituting a housing for stove fixture elements, and a stove back wall at the rear of the fence base member, adjacent edges of said back walls being in overlapping relation when the top fence member is in erected position.

8. A stove or range including a top having an upwardly projecting chambered fence base member formed integrally therewith and having upwardly projecting enclosing walls, a top chambered fence member having enclosing walls complementary to the walls of said fence base member, vertically elongated sockets mounted upon and housed within said fence base member to depend therein adjacent the ends thereof, vertically elongated tongues carried by and projecting from the bottom of said top fence member in inwardly spaced relation to the walls thereof and positioned for vertically sliding engagement within said elongated sockets in the chamber of said fence base member when the top fence member is in erected position upon the fence base member, said top fence member being removable as a unit from said fence base member to facilitate crating of

the stove; and a joint strip secured to one of said fence members to telescopically overlap the other when the top fence member is in erected position thereby covering the joints between the members.

9. A stove or range including a top having an upwardly projecting chambered fence base member formed integrally therewith and having upwardly projecting enclosing walls, a top chambered fence member having enclosing walls complementary to the walls of said fence base member, vertically elongated sockets mounted upon and housed within said fence base member to depend therein, and vertically elongated tongues carried by and projecting from the bottom of said top fence member in inwardly spaced relation to the walls thereof and positioned for vertically sliding engagement within said elongated sockets in the chamber of said fence base member when the top fence member is in erected position upon the fence base member with the socket and tongue members entirely concealed therein, said top fence member being removable as a unit from said base fence member to facilitate crating of the stove.

10. A stove or range including a top having an integral relatively low base chambered fence member at the rear thereof and having upwardly projecting enclosing walls, a relatively high top chambered fence member having walls complementary to the walls of the fence base member, and tongue and socket coupling members vertically elongated and mounted on said base and top members for detachable vertically sliding engagement with each other and acting to support the top member in erected position on the base member and permitting removal of the top fence member as a unit, said coupling members being so arranged that the one carried by the fence base member is housed and concealed within the fence base member and the one carried by the top fence

member projects therefrom but is concealed when the top fence member is in erected position.

11. A stove or range including a top having a chambered base fence member at the rear thereof, said base fence member having front and end walls, a chambered top fence member having front and end walls complementary to the front and end walls of the base fence member, vertically disposed socket members secured to one of said fence members adjacent the ends thereof, and vertically disposed tongue members secured to the other of said fence members for detachable vertically sliding engagement within said socket members, said socket and tongue members being in engaging relation with each other and disposed in the chamber of one of said fence members when the top fence member is in erected position on the base fence member, said tongue members being plate-like and disposed generally in planes substantially at right angles to the front wall of the fence member to which the tongues are secured.

ALFRED J. REEDY.
